SUCTION CLEANER

Charles G. Troxler, North Canton, Ohio, assignor
to The Hoover Company, North Canton, Ohio,
a corporation of Ohio

Application December 29, 1938, Serial No. 243,286

15 Claims. (Cl. 15—8)

The present invention relates to suction cleaners in general and more particularly to a new and novel agitator for a suction cleaner. More specifically the invention comprises a rotary agitator for a suction cleaner which embodies automatically adjustable brushes which are positioned at their optimum radial adjustment at the beginning of each period of agitator rotation.

It is an object of the present invention to provide a new and improved agitator. It is a further object of the invention to provide a new and improved rotary agitator for a suction cleaner. A further object is to provide a new and improved rotary agitator embodying brushes which are automatically adjusted to compensate for wear. A further object of the invention is to provide a suction cleaner rotary agitator embodying agitating elements subject to wear which are automatically adjusted to compensate therefor by means including an inertia release. A further object of the invention is to provide an agitator for a suction cleaner in which at the beginning of each period of use the agitator brushes are automatically released by means including an inertia member to be thrown centrifugally outward to a definite radial extent and thereafter are drawn inwardly to their optimum working position as the agitator reaches a fixed speed of rotation. These and other more specific objects will appear upon reading the following specification and claims and upon considering in connection therewith the attached drawings to which they relate.

Referring now to the drawings in which a preferred embodiment of the present invention is disclosed:

Figure 1 illustrates a modern suction cleaner with certain parts of the casing broken away to show the invention embodied therein;

Figure 2 is a section through the agitator upon the line 2—2 of Figures 1 and 4.

Figure 3 is an exploded view of the brush adjustment mechanism of the agitator;

Figure 4 is a transverse section upon the line 4—4 of Figure 2 and illustrates the relationship of the brush adjustment mechanism with the agitator rotating at a fixed speed;

Figure 5 is a view similar to Figure 4 and illustrates the relationship of the brush adjusting parts with the agitator accelerating at the beginning of a period of rotation;

Figure 6 is a section upon the line 6—6 of Figure 2 and discloses the brush elements slidably positioned within the brush seat and the adjusting means connected thereto.

To clean effectively a surface covering an electric cleaner must embody means to agitate the covering to dislodge therefrom the embedded foreign material, and additionally means to create a flow of air which will carry the dislodged foreign material from the covering to a suitable receptacle. The most widely accepted agitating means for the suction cleaner comprises a rotary agitator which embodies both rigid beating elements and flexible brush elements. The brush elements are normally made of animal hairs which gradually wear away with the use of the agitator. As both the brush elements and the beater elements of the agitator must project substantially the same radial distances in order that both may be effective in agitator rotation, it follows that as the brush element wears away it will in time become entirely ineffective. In the old type of agitators it became necessary to remove the worn brush element and to replace it by a new element. Later agitators embodied means by which the brush element could be adjusted manually to a plurality of positions as the brush became worn to compensate for wear. In the agitator constructed in accordance with the present invention the brush element is automatically repositioned each time the agitator is placed into use and is adjusted to a position at which its extension is substantially equal to or slightly greater than that of the beater elements, depending upon the wishes of the designer.

The automatic adjustment of the present invention is operated upon a new and novel principle in which the acceleration of the agitator at the beginning of each cleaner use period releases the brushes by an inertia mechanism to permit them to fly outwardly under centrifugal force into contact with a shoe which surrounds the agitator within the cleaner nozzle. Thereafter, and as the agitator attains a constant speed of rotation, spring means cause the brush to be withdrawn a predetermined distance from its contact with the positioning shoe, the inertia means being ineffective with the agitator rotating at a constant speed. By the terms inertia means and inertia mechanism, as herein used, it is the intent to distinguish from the usual centrifugal means and mechanisms which make use of centrifugal force. As herein used, inertia means and inertia mechanisms are those actuated by change in the speed of rotation of the agitator rather than by forces set up or generated by the speed of rotation itself.

Referring again to the drawings in Figure 1 a modern suction cleaner is illustrated in which

the cleaner main casing is seen to comprise a nozzle 1 having surface-contacting front and rear lips 2 and 3, respectively. The nozzle is interiorly connected by an air passageway 4 to the eye 5 of the fan chamber 6 within which is positioned the suction-creating fan 7. An exhaust outlet 8 extends rearwardly from the fan chamber 6 and to its rear end is attached, by manually-operable means 9, a removable filter bag 10. An unshown driving motor is positioned within the motor casing 11 immediately above the fan chamber 6, the motor functioning to drive the fan which is carried by the motor shaft 12. A driving pulley 13 is formed upon the lower extremity of the shaft 12 which drives the power-transmitting belt 14 extending forwardly through the air passageway 4 to encircle the agitator, indicated generally by the reference character 15 within the nozzle 1. The cleaner is movably supported upon front wheels 16 and rear wheels 17 and, as in the usual cleaner, a pivoted handle, the lower end of which is indicated at 18, is provided by which the operator can propel the machine in operation. In general arrangement and function the parts hereinafore described are as in the usual cleaner.

The cleaner agitator 15 comprises an elongated cylindrical body 20 which is formed substantially midway of its length with a groove portion 19 which functions as a pulley to seat the power-transmitting belt 14. Each end of the agitator is closed by an end plate 21 which is centrally recessed to seat a bearing 22. The inner race of the bearing seats upon an elongated supporting shaft 23 which extends the length of body 20 and from the opposite ends thereof. A thread guard plate 24 is threaded upon each end of shaft 23 and overlies the adjacent end plate 21 to protect the adjacent bearing 22.

The agitating elements of the agitator comprise elongated helical rigid beater elements 26 which extend from substantially common points at the ends of the agitator. Cooperating with the rigid beater elements 26 are flexible brush elements 27 each of which comprises a series of brush tufts 28, 28 which are mounted in an elongated rigid back 29 which is itself slidably positioned within a brush seat 30 formed in the agitator body 20. The brush seats are open-bottomed and axially extending and are closed by the brush back 29 which fits closely therein.

The brushes 27 are not fixed to their seats 30 and each brush instead is mounted upon a rod 35 which is positioned within the brush seat by two plates 37 each of which is pivotally connected along one of its sides to the rod 35. At their opposite sides the plates are pivotally connected to rods 38 which extend the length of the agitator to be slidably positioned at each end within a slot 39 which extends radially and transversely of the brush seats 30. The slots 39 are formed in two plates 40 which are positioned within the agitator body adjacent the inner sides of end plates 21. Each plate is formed with a centrally located boss 41 through which the agitator shaft 23 extends. These plates 40 also serve as the outer end of the brush seats 30.

It is apparent that the connecting plates 37, which are attached to each brush and are joined by the elongated rods 38, insure the conjoint and synchronous movement of the brushes upon the opposite sides of the pulley. Any radial movement of either brush in its seat causes its connecting plates 37 to be drawn together or moved

apart in an obvious manner resulting in the rods 38 moving toward or from each other and thereby producing identical movement of the plates and the brush in the remaining brush seat.

The plates 40 function as the mounting means for the brush positioning and locking mechanism. This mechanism comprises a slotted collar or slide 44 which slidably encloses the boss 41 of the supporting plate 40 and which is slidably held against the plate 40 by the headed end of the adjacent brush supporting rod 35. The rod 35 also passes through a slot 45 formed in the plate 40 which extends parallel to the brush seat 30 and perpendicularly to the slots 39. Slide 44 is formed upon one side with a ratchet 46 comprising a series of aligned teeth. Rotatably mounted upon the plate boss 41 adjacent the slide 44 is a pawl 48 combined with an inertia weight 49 and formed with one or more teeth which are adapted to mesh with the teeth of the slide ratchet 46. A coil spring 51 is fixedly hooked to the adjacent plate 40 at one of its ends with its opposite end lying against the pawl 48, the relationship being such that the spring at all times urges the pawl in a counterclockwise direction, as viewed in Figures 4 and 5, and to the upper limit of its angular travel, as viewed in those figures, as defined by the pawl-stop pins 52. With the pawl held in this position, its normal position in agitator use and as illustrated in Figure 4, the pawl meshes with the ratchet 46 and the brushes 27 are fixedly positioned within the agitator body.

Cooperating with the agitator carried brush positioning and locking mechanism are a pair of brush contacting shoes 55 which are mounted within the nozzle 1 in encircling relationship to the agitator for a major portion of its periphery adjacent each end thereof. The shoes 55 are positioned at a predetermined distance from the axis of agitator rotation and are adapted to be contacted by the brush elements of the agitator only when those elements are extended beyond their normal working positions.

The operation of the agitator constructed in accordance with the present invention is as follows:

Upon the cleaner being placed into operation, as by the operator closing the motor controlling switch, the suction-creating fan and the driving pulley 13 are rotated. The fan is effective to create a flow of air through the cleaner nozzle, through the fan chamber and through the exhaust outlet 8 into the dust filter bag 10. A reduced pressure is created within the nozzle 1 which is effective to lift a surface covering undergoing cleaning into contact with the lips 2 and 3 of the nozzle and with the agitating elements of the agitator 15. The agitator is rotated by the belt transmitted power from the pulley 13 and during the period of time in which the motor picks up speed at the beginning of its operation the agitator also is accelerated. During the period of acceleration the inertia of weight 49 overcomes the pivoting force exerted upon the pawl 48 by the spring 51 and causes the pawl to move from its position illustrated in Figure 4 to the position illustrated in Figure 5 in which it is in contact with the trailing stop pin 52. In this position the teeth of the pawl 48 do not mesh with the teeth of the slide-carried ratchet 46 which is connected directly to the brush-carrying rods 35. As the action is identical at the two ends of the agitator, the brush elements 27 are released and are thrown

radially outward in their seats 30 under the action of centrifugal force. In this released condition during the major portion of 360 degrees of rotation the extremities of the brush elements are in contact with the surrounding shoes 55, and the outer radial brush position is determined by this contact with the shoes. Across the open mouth of the nozzle the brushes will contact the lifted surface covering but this interval is relatively short and the radial position of the brush will be determined by its contact with the surrounding shoe.

So long as the agitator continues to accelerate under the actuation of the driving motor this brush-released relationship will continue and, regardless of the length of the bristles 28, the brush will extend to the shoes 55 unless, of course, they are so worn that they are no longer able to extend that far. As the cleaner operation continues, however, the normal speed of operation and rotation of the agitator will be reached at which time there will be no inertia force acting upon the weights 49 and the pawl 48, acting under the pivoting force exerted by the coil spring 51, will be pivoted in a counterclockwise direction, as viewed in Figures 4 and 5. Before the weight 49 has contacted the forward or leading stop pin 52 the teeth of the pawl 48 will have meshed with the teeth of ratchet 46 and the further movement of the pawl as the inertia 30 weight advances to the forward stop pin 52 will result in the slide 44 being moved inwardly upon the plate 40 a predetermined distance. The extent of this movement is always the same for the pawl teeth always contact the ratchet teeth 35 at the same angular position and rotate thereafter through a fixed angle. This radial movement of slide 44 also results in the inward radial movement of the brush-carrying rod 35 to which it is attached and with the rod, of course, the 40 brush 27 moves radially inward in the brush seat. The synchronous adjustment of the brushes at the opposite ends of the agitator is insured by the interconnecting mechanism comprising the plates 37 and the elongated rods 38. With the pawl 48 in its operating and constant speed position the slide 44 will have been moved inwardly radially a fixed extent and the brush elements 27 also will have been withdrawn radially a fixed distance from their contact with the encircling shoes 55. This distance is so fixed that the brushes in their locked position have the correct radial extension relative to the axis of agitator rotation and also relative to the extension of the beater elements 26.

It is clear that each time the cleaner and the agitator are placed into operation this period of adjustment for the brush elements will occur, and the wear of the brush element which has previously taken place with use and which has decreased the bristle length will not affect the final position to which the brush element is set until such a time as the brush has become so worn that it is no longer able to move outwardly into contact with the encircling shoes 55. At that time no further proper adjustment is possible and the brush is considered worn out and of necessity requires replacement. Before that time has been reached, however, the life of the brush has been greatly increased by permitting its continued use and effectiveness long after it would have become ineffective had its position not been corrected.

I claim:

1. In a rotary agitator for a suction cleaner, 75

a radially movable agitating element subject to wear in use, and means to adjust said element radially to compensate for such wear comprising means to release said element during a period of agitator acceleration to move radially outward under centrifugal force, and means to withdraw said element radially a predetermined distance upon the agitator reaching a constant speed of rotation.

2. In a rotary agitator for suction cleaners, a radially adjustable agitating element, inertia-operated means to release said element for radial movement during the accelerating period of said agitator, and means to lock said element at a fixed position with said agitator rotating at constant speed.

3. In a suction cleaner, a rotary agitator including a radially adjustable agitating element, inertia-operated means to release said element to be thrown radially outward by centrifugal force during an accelerating period of said agitator, and means to withdraw said element radially a fixed distance with said agitator rotating at constant speed, and means carried by said cleaner to limit the extent of outward radial movement of said element.

4. In combination in a suction cleaner, a rotary agitator including a body and a rigid beating element and a flexible brushing element therein, means mounting said brushing element for radial movement on said body, inertia-operated means to release said brushing element to be thrown radially outward during a period of acceleration of said agitator, and means to withdraw said brushing element a predetermined distance at the termination of said period, and a shoe within said nozzle adapted to contact said brushing element to limit its outward radial movement.

5. In a suction cleaner, a rotatable agitator, an agitator element radially movable by centrifugal force, stationary means to limit the radial movement of said element, inertia-operated means to release said element for outward radial movement during a period of rotational speed change, and spring means to withdraw said element a predetermined distance at the end of said period.

6. In a suction cleaner rotary agitator, a rotatable body, a brush seat in said body, a brush radially movable in said seat, means controlling the radial movement of said brush including a ratchet, a pawl to move and to fix the position of said ratchet, spring means urging said pawl in one direction and into contact with said ratchet, and an inertia weight carried by said pawl to overcome the force of said spring to move said pawl from said ratchet during the acceleration of said agitator.

7. In a suction cleaner rotary agitator, a rotatable agitator body, an agitating brush mounted for radial movement on said body, a brush positioner element connected to said brush and mounted for pivotal movement on said body under its inertia in the acceleration of said body, and spring means to overcome the inertia of said positioner element with said agitator rotating at constant speed to actuate said positioner element to move said brush a predetermined distance radially.

8. In a rotary agitator for a suction cleaner, a brush element, means to position said element radially including an inertia weight to release said brush for outward radial movement during agitator acceleration and spring actuated means

to fix said brush in an inner radial position in which said brush has a constant radial extension during constant speed rotation.

9. In a suction cleaner rotary agitator, a radially adjustable brush, automatic means to move and secure said brush at a predetermined radial extension, and an inertia weight connected to and adapted to overcome said means to release said brush temporarily and operable upon the acceleration of the agitator.

10. A rotary agitator for a suction cleaner, comprising a brush element subject to decrease in size with wear, means mounting said element for radial adjustment relative to the axis of rotation to compensate for wear, and spring-pressed inertia-operated means actuated by a change in agitator speed of rotation to reposition and fix said brush in position.

11. In a rotary agitator for a suction cleaner, a brush, means supporting said brush for radial movement, a brush positioner to move and to fix the radial position of said supporting means, inertia-operated means to release said positioner during agitator acceleration, and spring means to move said positioner into operative position at the termination of a period of acceleration.

12. In a rotary agitator for a suction cleaner, a plurality of arcuately spaced radially movable agitating elements subject to wear in use, and means to adjust said elements simultaneously and radially to compensate for such wear comprising means to release said elements to move radially outward under centrifugal force, and means to withdraw said elements simultaneously and radially a predetermined distance upon the agitator reaching a constant speed of rotation.

13. In a rotary agitator for a suction cleaner,

5 a rotatable hollow cylindrical body, a plurality of interconnected arcuately spaced radially movable agitating elements subject to wear in use mounted in said body, and means to adjust said elements simultaneously and radially to compensate for such wear comprising means to release said elements to move radially outward relative to the axis of rotation of said body under centrifugal force, and spring-actuated means to withdraw said elements simultaneously and radially a predetermined distance upon the agitator reaching a constant speed of rotation.

10 15 14. In a suction cleaner, a rotatable agitator, an agitating element radially movable relative to the axis of rotation by centrifugal force and having an optimum position, stationary means to limit the outward displacement of said element to a radial position slightly greater than its optimum position, inertia-operated means to release said element during agitator acceleration to move outwardly into contact with said stationary means, and means automatically operable upon said agitator reaching a constant speed of rotation to retract said element to its optimum radial position at which it does not contact said stationary means.

20 25 30 35 15. In a rotary agitator for a suction cleaner, a radially movable agitating element subject to wear in use, and means to adjust said element radially to compensate for such wear comprising means to release said element during the period said agitator is being placed into operation to move radially outward under centrifugal force, and means to withdraw said element radially a predetermined distance upon the agitator reaching a constant speed of rotation.

CHARLES G. TROXLER.
